TYPE TYING-UP DEVICE

Wilibald Stolle, Freital in Saxony, Germany

Application October 21, 1938, Serial No. 236,252
In Germany October 26, 1937

2 Claims. (Cl. 101—404)

This invention relates to a device for tying up type.

Set up type is usually tied up by means of a page cord, and when changes or corrections have 5 to be made, particularly in letterpress printing, the cord has to be loosened for each of these operations and after completion of the latter rearranged to insure good tying up of the type. This is quite bothersome and involves, moreover, the 10 risk of disarranging or pieing the unsecured matter or parts thereof, and this danger exists also, and to a still higher degree, when the matter is inserted in the press, as this operation requires the removal of the cord and brings about a 15 placement of the type.

Attempts made to overcome these defects by employing toothed furniture have not been satisfactory for the reason that too large stocks were needed, and the use of such members involved, 20 furthermore, considerable wear and tear resulting in serious inaccuracies.

The invention eliminates the difficulties mentioned in a reliable manner by providing a tying up device which remains attached to the matter 25 during its correction as well as during insertion in the machine, so that the matter need be tied up only once.

The device according to the invention comprises a frame two opposite sides of which are made up 30 of locking members, grooved furniture or spacers and offset wedges, and the other two sides are formed of plain spaces or furniture, the sides being surrounded by a page cord anchored to the locking members. The cord lies in the grooves of the 35 locking members, furniture or spaces and hugs the offset face of the wedge member, but is exposed above and below on the smooth or plain furniture.

During insertion of matter in the machine the 40 exposed portions of the cord are therefore covered by furniture or spaces having longitudinal grooves.

To exchange type the matter is loosened up by withdrawing a wedge member or quoin and slightly displacing the associated locking member. 45 When the latter is moved back and the quoin inserted again, the frame is as rigid as before and the matter firmly tied up.

The page cord preferably has a length equal to 50 five times the diagonal of the matter, as in case of longer cords the locking members cannot be displaced any more in lateral direction. The cord extends from one locking member around the entire matter to the other locking member and thence around the matter again back to the sec-

ond locking member. In this way it becomes possible to arrange at will the reglet with its clamping disc and the wedge member on the longitudinal or cross sides.

The invention is illustrated by way of example 5 in the accompanying drawing, in which

Figure 1 is a top view of matter tied up by the device according to the invention;

Fig. 2 is a piece of furniture shown in elevation;

Fig. 3 is an elevation of a lock member or quoin; 10

Fig. 4 is an elevation of a lock member;

Fig. 5 is a view of one side of the device; and

Fig. 6 is a diagrammatic view of the course of the cord.

On each of the two long sides of the matter 1 a lock member and two furniture members 3 having a broad groove 2 are arranged between which a wedge member or quoin 4 comprising a border piece and a pointed plate is inserted.

The lock members each of which consists of a 20 plate 5 provided with a clamping disc 6 and recessed members 7 are disposed opposite each other.

Each quoin 4 has an opening 8 to be engaged by an awl for removal. 25

The shorter sides of the matter 1 are covered by pieces of furniture 9 or spaces 10 of standard type.

The page cord 11 extends from one lock member around three sides of the matter 1 to the other 30 lock member where it is tied and is then conducted in the same direction around the entire matter and tied up at the second lock member. The cord 11 is arranged in sunken position in the furniture, quoins and locking members but freely 35 exposed on the faces of the furniture pieces 9 and of the spaces 10. When matter is to be placed in the machine, the exposed portion of the cord 11 is covered by members 12 corresponding exactly to the furniture members 3 but abutting with their 40 grooves 2 against the members 9.

I claim:

1. A device for tying up set type, comprising a frame formed of longitudinally grooved furniture members, a page cord surrounding said frame, a 45 plate fitted with a clamping disc, and a quoin, said plate and quoin being inserted in each long side of the frame instead of the corresponding furniture members.

2. A device according to claim 1, in which the 50 quoins consists of a plate having a thickness corresponding to that of the grooved furniture members at the cross section thereof.

WILIBALD STOLLE.
